CENTRIFUGAL REFRIGERATING APPARATUS

Robert W. Waterfill, Montclair, N. J., assignor to
 Buensod-Stacey Air Conditioning, Incorporated,
 New York, N. Y., a corporation of Delaware

Application September 30, 1938, Serial No. 232,580

10 Claims. (Cl. 230—117)

This invention relates to the general subject of artificial refrigeration, and in its more particular aspects to improvements in the design and construction of apparatus for practicing that art.

The principal object of the invention is to provide a centrifugal compressor unit in which the impeller or impellers of the respective stages are connected directly to the shaft of a driving motor thereby avoiding intermediate gearing, and are totally enclosed along with the motor in a single casing in such a way as to obviate the need for expensive and often troublesome shaft-sealing devices.

It is a further object of the invention to provide for the lubrication of the bearings for the motor-impeller shaft of such a unit and, since these bearings are wholly enclosed and thus inaccessible, to do this in a manner which will require outside attention only at such rare times as it may become necessary to replace the small amount of lubricant which may be lost.

Yet another object of the invention is to control the normal frothing of the lubricating oil within the unit which results from the release of dissolved refrigerant vapors when the pressure or temperature of the oil is varied—to confine the reaction within an isolated part of the unit so that the light oil froth produced thereby may not be carried out of the lubricating system.

It is a further object of the invention to direct streams of refrigerant vapor through the impeller-motor bearings and along the shaft in opposition to any seepage of oil along that shaft beyond the bearing chambers; and to direct such vapor through the bearing chambers along with any oil froth which may be entrained thereby to appropriate settling chambers wherein the refrigerant vapor may be released from the oil and returned to its normal course, and from whence the freed oil may be passed back to oil reservoirs formed in the bearing chambers.

It is still another object of the invention to provide a mechanical refrigerating system utilizing a plurality of totally enclosed centrifugal compressor units arranged in series with each other, i. e., with one unit discharging compressed vapor into the inlet of the next, and which, because each unit includes its own individual driving motor, is both flexible and economical.

In accordance with the foregoing objects, and more specifically, the invention aims to provide a two-stage centrifugal unit comprising a pair of impellers carried directly upon the opposite ends of the shaft of an electric motor and supported by the conventional bearings for that

shaft, a cylindrical shell serving as a support and casing both for the motor and the impeller, and a pair of scrolls or diffusers mounted in the opposite ends of the shell for cooperation with the impellers and so arranged that one discharges its compressed refrigerant vapor over the motor to cool it, and into the inlet of the other for further compression; and to provide a lubrication system which is also wholly enclosed within the shell of the unit and adapted to supply oil continuously to the motor-impeller shaft bearings when the unit is operating, while preventing the escape and loss of oil from its defined path.

The full nature of the invention along with other objects and various features thereof will be more fully understood from a consideration of the following description read in connection with the accompanying drawings, in which:

Fig. 1 is a side elevational view of a complete refrigerating machine, including a pair of compressor units constructed and arranged in accordance with the present invention.

Fig. 2 is an end elevational view of the assembly of Fig. 1.

Fig. 3 is a sectional view of one of the compressor units of Fig. 1 taken on the line 3—3 of that figure.

Fig. 4 is a sectional view taken on the line 4—4 of Fig. 3.

Fig. 5 is a vertical section, on an enlarged scale, of the lubrication system of the present invention as applied to one of the bearings of the vertically disposed compressor unit of Fig. 4.

Fig. 6 is an end elevational view, partly in section, illustrating the application of the improved lubricating system to one of the bearings of a horizontally mounted compressor unit.

Fig. 7 is a sectional view, on an enlarged scale, of a part of the lubrication system of Fig. 6, and

Fig. 8 is a sectional view of a fragment of a lubrication system according to the present invention embodying another means for inducing a flow of refrigerant into the bearing chamber.

In the drawings Figs. 1 and 2 illustrate a complete refrigerating system including a cooler 8, condenser 9, and a pair of totally enclosed compressor units 10 and 11 constructed in accordance with the present invention and mounted directly upon the cooler and condenser, respectively.

Thus the first unit 10 is bolted to the cooler in such position that the impeller 12 (Fig. 4) of its low-pressure stage 13 draws refrigerant vapor directly from the cooler and discharges it through scroll 14 into the casing 15 of the unit and over the motor 16 to cool it. The partially

compressed vapor is then intaken by the impeller 17 of the second and high-pressure stage 18, and after further compression, is discharged from the scroll 19 into a header 20 (Fig. 1) from whence it is conveyed through a manifold 21 to a second, and substantially identical header 22 bolted to the casing of the second unit 11.

This second unit is inverted with respect to the first one, that is, its low pressure stage 13 is located in the upper end of its casing while its high pressure one, 18, is mounted in the lower end thereof. Accordingly, the refrigerant vapor passes from header 22 into the low pressure stage of unit 11, and is finally discharged from its high pressure stage directly into the condenser 9.

The two units are of substantially identical design and construction. A description of one of them, 10, will accordingly suffice. That unit is well shown in Figs. 3, 4 and 5. Referring first to Fig. 4, it will be seen that the casing 15 is preferably a cylindrical steel shell having three radially-disposed ribs 23 welded to its inner surface at spaced points which serve to support the motor 16. It is particularly to be noted that the motor is bolted only to the upper ring 24 carried on the inner edge of the ribs, the lower ring 25 merely engaging the motor casing near its lower end to prevent radial movement while allowing free play to any expansion or contraction of the motor housing.

The design of the compressor stages is such that their constituent parts may be assembled in pancake fashion. Thus, and starting with the low pressure stage 13, at the bottom of the unit as shown in Fig. 4, the inner half 26 of the scroll or diffuser 14 is first fitted over the lower end of the motor shaft 27 and is bolted to the shoulder 28 of the flange 29 of the casing. If not already in place, the gland 30 is slipped over the shaft and bolted to the part 26 to provide a labyrinth packing surrounding the shaft at this point. The impeller 12 is next fitted and keyed to the shaft 27, and the spanner nut 31 is then applied. When that has been done the outer half 32 of the diffuser 14 is set in place over the impeller and bolted to the inner half 26. Finally the inlet guard 33 is bolted to the outer half 32 of the diffuser with its smoothly rounded outer surface merging with the curved inlet 34 of the impeller. The inlet guard carries a gland 35 having a grooved inner face which is now disposed in closely spaced relation to the adjacent outer surface of the reversely turned lip 36 of the impeller inlet to form a labyrinth packing adapted to prevent the short circuiting of compressed refrigerant from the outer periphery of the impeller into the inlet thereof.

The assembly of the second stage of the compressor, 18, is substantially identical with that just described. Specifically, the inlet guard 37 is first applied to the inner half 38 of the diffuser 19, and that inner half is then bolted to the shoulder 39 of the upper flange 40 of the casing. The impeller 17 is next set in place on the upper end of the shaft, suitably keyed thereto, and fixed in position by the application of nut 41. When properly done, the reversely turned lip 42 of the impeller inlet will be disposed closely adjacent the grooved gland 43 of the inlet guard 37 to form a labyrinth packing at this point adapted to prevent the short circuiting of compressed refrigerant from the outer periphery of the impeller back to its inlet. The assembly is completed by bolting the upper half 44 of the diffuser 19 to the vanes 45 of the lower half 38.

The motor-impeller shaft 27 is supported in ball-bearings 46 and 47 disposed in appropriate recesses formed in the opposite ends of the motor frame. These bearings are of somewhat conventional design, and are adapted to carry both the radial and thrust loads imposed upon the shaft. It is to be noted that only the lower one, 46 (Figure 4) is positively anchored to the frame of the motor which may conveniently be done by clamping its outer race 48 between a shoulder 49 of the flange 50 defining the bearing recess, and a similar shoulder of the gland 51 which forms a labyrinth packing surrounding the shaft at 52. The upper one, 47, merely has its outer race 53 slidably disposed within the bearing recess defined by the flange 54 so that it may have a limited movement in an axial direction and thus accommodate expansion and contraction of the shaft.

20 The lubrication of these bearings presents several special problems. It is not sufficient merely to provide for a continuous flow of oil to the balls. It is of equal importance to prevent the loss of oil. These problems have been solved in the present instance by providing each bearing with an oiling system of novel design, which features, among other things, a very small oil capacity such as will minimize the possible quantity of froth produced by breathing, means for 25 confining the froth within its proper sphere, and the avoidance of an independent oil pump. Since they are both identical in principle, and substantially so in construction, a description of one will suffice.

30 The system for the upper bearing is shown on an enlarged scale in Fig. 5. By referring to that figure it will be seen that the bearing lies wholly within a closed chamber 55, defined by the end piece 56 of the motor frame and the closure plate 57, with its slinger 58 dipping into the oil reservoir 59. Other constructional details, and their 35 importance, will best be understood by a consideration of the operation of the system.

35 When the compressor unit is in operation the motor shaft 27 drives the ball spacer ring 60 and its slinger ring 58, and the latter rotates the oil in the reservoir. This action is confined, however, to the oil in the well 61 which, it will be noted, is separated from the main body of the reservoir by the flange 62 and has access thereto only through one or more openings 63. The whirling oil is lifted, by centrifugal force, between the outwardly tapering outer surface of the slinger and the adjacent outwardly sloping surface of the flange 62, and is thus conveyed to the balls and races to lubricate them. Some oil may tend to rise between the inner surface of the slinger, and the adjacent surface of the sleeve 64 which constitutes the inner wall of the well. Any such action is largely avoided, however, by reason of the inward slope which is purposely given these surfaces. Specifically, the force of the whirling oil reacting against these sloping surfaces tends to drive the oil downwardly rather than upwardly. Any oil that does rise in this space, however, eventually reaches the annular groove 65 and is promptly relieved by centrifugal force through the radial openings 66 in the slinger, and passes back into the reservoir.

40 It is possible that some oil may get by the collecting groove 65, or may be thrown downwardly from the balls, and tend to work its way back along the surface of the shaft liner 67. Any such seepage, of course, would represent lost oil—it

would not be returned to the reservoir, but could only be entrained by the refrigerant vapor and carried to some remote point in the system. If such seepage were permitted the reservoir would soon be exhausted. The replacement of oil so lost from an outside source would not represent a solution to the problem, for that oil is lost only to the bearings. It would soon collect and clog some part of the refrigerant circuit thus interfering with continued operation. In order to prevent seepage in this way, the scroll 19 of the high pressure stage of the unit (Fig. 4), is tapped at 68, and a small volume of the compressed refrigerant vapor is led through conduit 69 to an annular groove 70 in the sleeve 64 surrounding the shaft liner. The compressed vapor tends to flow in both directions from this point, some passing the adjacent labyrinth rings 71 and immediately rejoining the main refrigerant vapor stream in the casing 15, the remainder passing upwardly along the liner 67 and into the bearing chamber 55. It is evident that the latter flow is in direct opposition to any oil seepage along the shaft. Hence it forces any escaping oil back into the collecting groove 65 for discharge into the chamber and reservoir.

The oil in the system is at all times in contact with refrigerant vapor, and this, whether the machine is idle or in operation. This vapor, particularly when miscible with the oil, is absorbed therein to a greater or lesser extent, dependent upon the temperature of the oil and the pressure surrounding it. Accordingly, when the pressure is reduced, and particularly when it is suddenly reduced at the time of starting the machine, the dissolved refrigerant is released. Just as in boiling thick liquids, the release produces a large volume of light froth which is principally refrigerant vapor but, of course, contains some free oil. If it is allowed to pass directly into the main stream of refrigerant, the oil will not only be lost to the bearings, but will subsequently collect and clog some part of the refrigerant circuit. The capacity of the oil reservoir is therefore made quite small in an effort to reduce the possible volume of foam, and the liquid level therein should not be permitted to rise much above the point indicated in Fig. 5. In addition, it will be noted that the closure plate 57 flares abruptly outward from the top of the reservoir so that any froth which is generated must spread in a thin layer over a comparatively large area, thus producing a condition which is most conducive to a prompt breaking up of the froth bubbles and a settling of the oil. The relative dimensions of the reservoir and adjacent frothing space can not be stated precisely. It is preferred, however, that the average area of the space shall be at least from four to eight times that of the oil, and that the volume of the space shall be from six to ten times the capacity of the reservoir. With this arrangement, even though frothing occurs at more or less regular intervals, the foam will promptly spread out and immediately start to break up as above pointed out. Some of it may, of course, find its way through the conduit 72, along with escaping vapor, and into the settling chamber 73. There, however, it can merely break up, the vapor passing out through the open upper end 74 of the chamber into the casing where it joins the main refrigerant stream, and the oil settling and returning to the reservoir through line 15. In any event, all foaming is confined either within the bearing chamber or the settling chamber 75

where it is protected from entrainment by the main refrigerant stream.

The settling chamber (Fig. 4) is mounted on the main wall of the casing 15 with its leg 76 projecting therethrough and provided with a bulls-eye 77 which gives a visual indication of the quantity of oil in the system. If the level is below normal, then additional oil may be supplied through conduit 78 formed in the base of the settling chamber, and, of course, that conduit may be used to drain the system should that be necessary.

The upper end of the bearing chamber 55 (Fig. 4) is located immediately below the inlet of the second compressor stage 18. In view of this close proximity, it is possible that some of the light oil froth may be drawn from the chamber through the bearings and openings 79 (Fig. 5) past the labyrinth groove 80, and along the shaft into the inlet of impeller 17. In order to oppose any such flow a small volume of compressed refrigerant is directed, from conduit 69, into the annular groove 81 in the gland 82. From there the refrigerant vapor tends to flow in opposite directions along the shaft 18, a part of it immediately escaping by the labyrinth packing 80 into the main casing 15, and the remainder passing into the chamber 83, and forcing any froth therein back through passages 79 into the bearing chamber. That vapor, along with any entering the chamber from groove 70, as previously described, eventually finds its way through conduit 72 and the settling chamber 73, back into the casing 15 where it again joins the main stream of refrigerant.

The compressor unit heretofore described is designed for mounting in a vertical position as shown in Fig. 1. Thus, the unit of Fig. 4 is adapted to have its flange 29 bolted directly to a corresponding one on the cooler 8 with its low pressure stage 13 in direct communication with the cooler. The second compressor unit 11 of Fig. 1 is, as has been said before, of identical construction except in so far as its compressor stages are reversed as compared with those of unit 10. It is not practical, of course, merely to turn the unit of Fig. 4 end for end in mounting it upon the condenser 9 of Fig. 1 because of the character of the lubricating system. The same thing can readily be accomplished, however, by merely reversing the positions of the separate stages 13 and 19. Thus, in the unit 11, the impeller 12 and scroll 14 will be assembled at the upper end of the motor shaft 27 as viewed in Fig. 4, and will be bolted to the shoulder 39 of the flange 40, while the impeller 17 and scroll 19 will be assembled at the lower end of the shaft and be bolted to the shoulder of flange 29. It may then be necessary to place a shield over the open end 74 of the settling chamber 73, or to make some other provision for preventing direct impingement of the main refrigerant stream upon the oil and path in the settling chambers. Aside from the foregoing, no other changes will be necessary, and the unit may then be mounted directly upon the condenser 9 as described.

The compressor unit may readily be designed for mounting in a horizontal position. To do so, it is merely necessary to make certain changes in the bearing lubrication systems, all other parts being designed and assembled in the manner shown in Fig. 4. A fragment of such horizontal unit, illustrating the lubrication system as applied to one of its bearings, is shown in Figs. 6

and 7. In that arrangement, the bearing 47a is mounted in a recess defined by the annular flange 87 formed as a part of the casting 88 which serves as an end of the motor frame; and lies wholly within the closed chamber 89, formed between the casting and a cap 90, the lower part of which is adapted to serve as a reservoir 91. Other constructional details of the system will best be illustrated by a consideration of the manner in which it works.

When the compressor unit is in operation, the slinger ring 92 is driven by the motor shaft 27a, and lifts oil from the reservoir to the sleeve 93. The slinger ring is not positively connected to the sleeve but is merely driven by friction. In order to prevent its rotation with the shaft and sleeve, as distinguished from being driven thereby, and the possibility that it may jump off the sleeve, the flange 94 is provided. The oil which is so deposited on the sleeve rises along its chamfered lip 95, and is then thrown between the bearing races and on the balls. So much for the actual lubrication of the bearings.

The prevention of the loss of oil from the chamber presents the next problem and will now be considered. The larger proportion of any oil which is thrown out of the bearings will immediately drain along the walls of the chamber, or fall directly into the reservoir. Some of it, however, may find its way along the shaft, to the right as viewed in Fig. 7, towards the shaft opening in the casing. Before it can reach that point, however, it will be caught in the peripheral groove 96 and be thrown back along its chamfered face towards the bearing. Similarly, any oil draining along the rear wall 97 of the chamber from points above the center line of the shaft, will be caught in the groove 98, and be directed into the peripheral groove 99 in the shaft. From there, it will be thrown backwardly along the chamfered face of this groove towards the bearing so that it may eventually work its way back to the reservoir.

The lip 100 formed on the left hand end of the sleeve 93 will, of course, throw some oil. Most of it, however, will immediately fall into the reservoir, or on some other wall of the casing, from whence it may promptly drain back to the reservoir. In spite of the foregoing precautions some small quantity of oil may work its way along the shaft and through the openings 101 and 102. Such seepage not only represents an actual loss to the bearings, but its presence in the refrigerant stream will cause trouble in the refrigerant circuit. To prevent this, a small quantity of refrigerant vapor is directed along the shaft through the openings and into the bearing chamber in direct opposition to any incipient flow of oil from the chamber along the shaft. Specifically, the high pressure stage is tapped, in the manner shown in Fig. 4, and compressed refrigerant is led through line 69a and the cored passages 105 and 106 to the annular grooves 107 and 108. From there the vapor flows in both directions, a part immediately escaping by the labyrinth packings 109 and 110 back into the casing 15a of the unit to rejoin the main refrigerant stream therein, and the rest flowing along the shaft and forcing any oil which it encounters back into the chamber 89.

In the system of Figs. 6 and 7 it will again be noted that the capacity of the reservoir 91 is small as compared with the remaining portion of the chamber. Adequate space is thus provided to accommodate any frothing which may

occur, and to allow the froth to break up and settle in a normal way. The worst that can happen during the frothing period is for some of the foam to pass out of the chamber through conduit 72a, along with the vapor introduced as above described, to the settling chamber 73a. There, as was described in connection with Fig. 4, the oil and refrigerant will promptly separate, the vapor passing back to the casing 15a, the oil returning to the reservoir through line 75a.

A pair of the horizontal units just described may be connected in series with each other and with a cooler and condenser to provide a complete system. Thus, if desired, one unit may be mounted upon the cooler, and another upon the condenser with appropriate connections thereto, much in the manner illustrated in Fig. 1. In another, and preferable arrangement, a pair of units may be disposed in end to end relation with their adjacent flanges bolted together, and with their opposite ends appropriately connected to the cooler and condenser, respectively.

In the oiling systems of both the vertically and the horizontally mounted units (Figs. 5 and 7) provision is made for inducing a flow of refrigerant vapor along the motor shaft into the bearing chamber in opposition to any outward seepage of oil along that shaft away from that chamber. The purpose, of course, is to force creeping oil back into the chamber—to prevent its loss through the shaft openings. In both instances it is effected by vapor taken from a tap on the high pressure stage and discharged into annular channels surrounding the shaft at the points at which it passes through the walls of the bearing chambers.

Another way of inducing this flow is illustrated in Fig. 8. There the shaft 27b carries a small impeller 115 disposed in closely spaced relation to the adjacent wall 116 of the bearing chamber. This impeller is nothing more than a disc which serves, when rotated with the shaft, to draw vapor from the casing 15 (Fig. 4) of the unit through the shaft opening 117 and to discharge it within the chamber from whence it may be released through a settling chamber such as 13, 73a (Figs. 4 and 6) in the manner hereinbefore described. In the preferred embodiment the impeller is disposed in a recess 118 in the wall of the casing so that any oil draining along the wall from above may not be caught by the impeller but may flow back into the bearing 47b or the base of the chamber in a normal fashion. As a further precaution the face of the shaft opening 117 is channeled at 119 to catch any oil which may creep by the impeller and to return such oil through the drilled passageway 120 to the base of the chamber.

The foregoing arrangement has been shown applied only to one of the shaft openings in the bearing chamber. That is all that is believed to be necessary to illustrate the idea involved. It will be readily evident to those skilled in the art that a similar impeller may be attached to the shaft on the opposite side of bearing 47b adjacent the opposite wall of the chamber to induce a flow of vapor inwardly through the other shaft opening. It will further be noted that this arrangement has been shown in connection with a lubrication system designed for use in a horizontally disposed unit such as has been particularly described in connection with Figs. 6 and 7. It is perfectly evident, however, that it can readily be adapted to use in a ver-

tically arranged system such as is shown in Fig. 5.

The centrifugal compressor operates most efficiently with refrigerants of the so-called "low pressure" class, and the ones here shown and described are particularly designed for such service. With many of them the entire refrigerating cycle is carried out at sub-atmospheric pressure. When a refrigerant of this group is used it is entirely possible to add oil to the lubricating system, while the unit is in operation, or at any time when it is under a vacuum. The procedure in such case is quite simple, involving nothing more than the filling of the oil cup 111 (Fig. 6) and the opening of the valve 112. Atmospheric pressure then forces the oil through conduit 78a into the settling chamber and thence to the reservoir. It will be noted that no pump or other accessories are necessary. It is important, however, not to allow the cup 111 to be entirely emptied during this process. If it is, then the entire system will promptly fill with air, thus requiring a purging operation before the unit can again be operated.

It will be apparent from the foregoing that all moving parts of the compressor unit, whether it be designed for vertical or horizontal mounting, to wit, the motor, the oiling systems and the impellers, are wholly enclosed within the single casing 15. There are no relatively moving parts projecting beyond the diffusers. There is, accordingly, no need for the provision of expensive and often troublesome shaft-sealing devices. In addition it is to be noted that no mention has been made of gaskets between the inner and outer halves of the diffusers, nor between the diffusers and the flanges to which they are bolted, and, as a general rule, none will be required. Any leakage of refrigerant vapor will be of infinitesimally small proportion; and the leakage, in any event, will only be between one part of the system and another, not from the system to the surrounding atmosphere. A further feature of importance is the fact that the impellers are mounted directly upon the opposite ends of the motor shaft, thereby doing away with intermediate gearing. In this connection it will be noted that the motor itself lies between the two compressor stages, and is cooled by the stream of partially compressed gas discharged from the first stage. The temperature of the motor may accordingly be kept at a considerably lower point than would otherwise be possible.

Since certain changes may be made in the embodiment of the invention and in the design, construction and arrangement of the various constituent parts, it is intended that the foregoing shall be construed in a descriptive rather than in a limiting sense.

What I claim is:

1. In a motor driven compressor unit a lubrication system for a shaft bearing comprising a chamber surrounding the bearing and having openings therein through which the shaft passes with a running fit and having its lower portion adapted to serve as an oil reservoir, a slinger driven by the shaft for supplying oil from the reservoir portion to the bearing, means for causing a flow of small volume of the gas being handled by the compressor through the shaft openings and along the shaft into said chamber to prevent seepage of oil along the shaft away from said chamber, and means for separating the gas from any oil which it may have entrained

in passing through said bearing chamber, said last mentioned means comprising a settling chamber having communication with the inlet of said compressor, a conduit connecting the upper portion of the bearing chamber with said settling chamber, and a second conduit connecting the lower portion of said settling chamber with the oil reservoir portion of said bearing chamber.

- 10 2. In a motor driven compressor unit having a shaft bearing mounted within the casing of the unit in the path of vapor, a lubrication system for such shaft bearing comprising a chamber surrounding the bearing and having openings therein through which the shaft passes with a running fit, an oil reservoir formed in the base of the chamber below the bearing, means for lifting oil from the reservoir to the bearing, means for causing a flow of a small volume of refrigerant vapor through the shaft openings and along the shaft into the chamber to prevent seepage of oil along the shaft away from the chamber, a settling chamber comprising a tubular shell having an open upper end located substantially on a level with the top of the bearing chamber and a closed lower end disposed substantially on a level with the base of the reservoir portion of the bearing chamber, a conduit connecting the upper portion of the bearing chamber with the settling chamber, and a second conduit connecting the bottom of the settling chamber with the base of the reservoir for returning oil to the bearing chamber.
- 15 3. In a totally enclosed motor driven vapor compressor unit including a shaft bearing mounted within the casing of the unit in the path of vapor, a lubrication system for such shaft bearing comprising a chamber surrounding the bearing and having openings therein through which the shaft passes with a running fit and having its lower portion adapted to serve as an oil reservoir, a slinger driven by the shaft for lifting oil from the reservoir to said bearing, and means connecting said chamber with the inlet of the compressor whereby to induce a flow of vapor through the shaft openings into said chamber, the volume of said chamber being on the order of a multiple of the volume of its reservoir portion, and the cross-sectional area of said chamber at a point above the normal oil level in its reservoir portion and below the bearing being on the order of a multiple of the cross-sectional area of said reservoir portion at the normal oil level, whereby any froth generated by the release of vapor from the oil in the reservoir may rise in the chamber and spread over a large area to facilitate its breaking up.
- 20 4. In a totally enclosed motor driven vapor compressor unit, a lubrication system according to claim 3, further characterized by the provision of a settling chamber comprising a tubular shell mounted within the casing of the unit with its upper end communicating with the inlet of the compressor and with its closed lower end disposed substantially on a level with the bottom of the reservoir portion of said bearing chamber, a conduit connecting the upper portion of said bearing chamber with said settling chamber for conveying oil froth and refrigerant vapor to said settling chamber, and another conduit connecting the bottom of said settling chamber with the bottom of the reservoir portion of said bearing chamber for returning oil from the settling chamber to the reservoir.
- 25 5. In a totally enclosed motor driven com-

pressor unit, a lubrication system, according to claim 3, further characterized by the provision of a settling chamber comprising an L-shaped tubular shell having its vertical leg mounted on the wall of the casing of the unit with its upper end communicating with the inlet of the compressor and its horizontal leg projecting through the wall of the casing substantially on a level with the base of said reservoir portion of said bearing chamber, a transparent member closing the end of the horizontal leg of said settling chamber, a conduit connecting the upper end of said bearing chamber with the upper portion of said settling chamber for conveying oil froth and refrigerant vapor to said settling chamber and another conduit connecting the bottom of said settling chamber with the base of said reservoir portion of said bearing chamber for returning oil to said reservoir.

6. In a totally enclosed motor driven compressor unit, a lubrication system according to claim 3, further characterized by the provision of a settling chamber comprising an L-shaped tubular shell having its vertical leg mounted on the wall of the casing of the unit with its upper end communicating with the inlet of the compressor and its horizontal leg projecting through the wall of the casing substantially on a level with the base of said reservoir portion of said bearing chamber, a transparent member closing the end of the horizontal leg of said settling chamber, a conduit leading from the bottom of the settling chamber to a point outside of the casing of the unit through which oil may be supplied to or removed from the lubricating system, a conduit connecting the upper end of said bearing chamber with the upper portion of said settling chamber for conveying oil froth and refrigerant vapor to said settling chamber and another conduit connecting the bottom of said settling chamber with the base of said reservoir portion of said bearing chamber for returning oil to said reservoir.

7. In a motor driven compressor unit, a lubrication system, according to claim 2, further characterized in that the settling chamber has a horizontal leg at its lower end which is adapted to project through the casing of the unit, a transparent membrane closing the end of such horizontal leg, and a conduit also adapted to pass through the casing of the unit to provide for the filling or draining of the lubrication system.

8. In a refrigerant compressor unit in which the compressor, its driving motor, and a shaft bearing are wholly enclosed in a substantially leak-tight casing, a lubrication system for such

shaft bearing comprising a chamber surrounding the bearing with openings therein through which the shaft passes with a running fit, said chamber having its base portion adapted to serve as an oil reservoir for the system, a slinger driven by the shaft for lifting oil from the base of said chamber to the bearing, means connecting said chamber with the compressor to cause a flow of refrigerant vapor through the shaft openings and along the shaft into said chamber to prevent seepage of oil along the shaft away from the chamber, means for separating refrigerant vapor from the oil to permit the vapor to return to the compressor, and means for returning the separated oil to the reservoir portion of the chamber.

9. In a motor driven vapor compressor unit having a shaft bearing mounted within the unit and lying in the path of vapor, a lubrication system for the shaft bearing comprising a chamber surrounding the bearing and having openings therein through which the shaft passes, the base of said chamber being adapted to serve as an oil reservoir, means for lifting oil from such reservoir to the bearing, means for introducing a flow of vapor through the shaft openings and along the shaft into said chamber to oppose any flow of oil along the shaft away from said chamber, means for separating the vapor from the oil whereby the vapor may return to the compressor and means for returning the separated oil to the reservoir portion of said chamber.

10. In a motor driven vapor compressor unit having a shaft bearing mounted within the unit and lying in the path of vapor, a lubrication system for the shaft bearing comprising a closed chamber surrounding the bearing with openings therein through which the shaft passes with a running fit, an oil reservoir formed in the base of said chamber beneath the bearing, means for lifting oil from the reservoir to the bearing, means for directing a small volume of compressed vapor from the outlet side of the compressor through the shaft openings and along the shaft into said chamber in opposition to any seepage of oil along the shaft away from said chamber, a settling chamber, a conduit for conveying refrigerant vapor and oil froth from the upper portion of said bearing chamber to said settling chamber, said settling chamber having its upper portion in communication with the inlet of the compressor whereby refrigerant vapor may be returned to the compressor, and a conduit adapted to convey oil from the base of said settling chamber to said reservoir portion of said bearing chamber.

ROBERT W. WATERFILL.
